WIRE CORE EXTRACTING MACHINE

Enrique Sauto y Hurtado de Saracho,
Mexico City, MexicoApplication December 19, 1944, Serial No. 568,924
In Mexico January 21, 1944

3 Claims. (Cl. 164—39)

1

This invention relates to apparatus for extracting the wire cores usually provided in the beads, rims or straps of tires and for extracting wire cores embedded in other material in a similar way. In other words, it relates to apparatus for the recovery of cores embedded in surrounding bodies.

The recovery of such wire cores is important because the salvaged materials can be reutilized for similar or other purposes.

A principal object of the invention is to provide apparatus that will make salvage operations simple and effective.

Another object of the invention is to provide apparatus that is comparatively simple in construction and effective for the purposes intended.

Another object of the invention is to provide a novel method of extracting cores from their surrounding bodies.

To the accomplishment of the foregoing and such other objects as may hereinafter appear, this invention consists in the novel method, construction and arrangement of parts hereinafter to be described and then sought to be defined in the appended claims, reference being had to the accompanying drawing forming a part hereof, which shows, merely for the purposes of illustrative disclosure, a preferred embodiment of the invention, it being expressly understood, however, that changes may be made in practice within the scope of the claims without digressing from the inventive idea.

In the drawing in which similar reference characters denote corresponding parts:

Fig. 1 is a perspective view of part of the apparatus utilized;

Fig. 2 is a plan view of the apparatus of Fig. 1;

Fig. 3 is a perspective view of another piece of apparatus used in the extraction of the wire cores; and

Fig. 4 is a fragmentary elevational view of a hooked instrument used in conjunction with other parts of the apparatus in the extraction of wire cores.

In the extraction of the wire cores from the rims or straps which have already been separated from the tires, or for the extraction of wire or other cores embedded in a surrounding body of other material in a similar way, it is first necessary to make cuts or incisions into the body of material surrounding the wire cores or rings in order to reach the cores or rings and thereafter to spread or open the cuts or incisions in a suitable press or vise to expose the cores or rings so that they may be removed with a conventional

2

hook shaped instrument or the like. When the straps or rims of the tires are removed from tires they are in the form of endless bands having the wire rings or cores surrounded by a soft body of rubber and other material of the tire structure. The apparatus of Figs. 1 and 2 is utilized to make the necessary cuts or incisions into the soft body. The apparatus of Fig. 3 is a press or vise that is used to spread the incisions so that the aforesaid hooked instrument can be utilized to pull the cores out of their bodies.

The apparatus of Figures 1 and 2 include a support table 10. This table is provided suitably with a movable carriage or car 11. Bearings 12 are provided on the carriage 11 and these in turn support a rotatable shaft 13 which carries a drum pulley 14 or the like. The shaft 13 (and with it the pulley 14) is freely rotatable in the bearings 12. The carriage 11 may be moved reciprocally 20 in its guideway 15 in any well known way, for example by the worm or screw 16 and hand wheel 17.

A second shaft 18 extending parallel with the shaft 13 is supported in the bearings 19 that are suitably attached to the support table 10. A transmission gear 20 is attached to the shaft 18 and meshes with the driving pinion 21 (Fig. 2) of a suitable motor 22 so that the shaft 18 may be driven or rotated. A drum pulley 23 or the like is fixed to the shaft 18. Teeth 24 are provided on the said pulley 23. These teeth, however, may be replaced by other suitable means, for example, a roughened surface that will serve to provide necessary friction for driving the endless straps or tire rims B (Fig. 2) which are to be carried on the pulleys 14 and 23 during cutting operations presently to be described. The pulleys 14 and 23 are supported in lateral alignment, and manipulation of the hand wheel 17 effects movement of pulley 14 with its carriage 11 toward or away from pulley 23 for a purpose to be presently described.

A second support table 25 is provided in conjunction with the table 10. This table may be integral with table 10 or if separate is preferably immovable with respect to the table 10. Such immovability may be provided in any suitable manner, for example, by the massiveness of the weights of the tables 10 and 25 or by actual physical attachment. A reciprocally movable carriage 26 is slidably supported in a suitable guideway 27 provided on the table 25. This carriage 26 may be moved reciprocally in its guide-way 27 in any well known manner, for example, by the screw 28 and hand wheel 29. The guide-way 27 is so ar-

ranged on table 25 that carriage 26 is movable reciprocally in a direction parallel with that of carriage 11.

A guideway 30 is provided in the carriage 26 which extends transversely of the direction of the guideway 27. A carriage 31 is slidably supported in this guideway 30. This carriage 31 may be moved reciprocally in its guideway 30 in any well known manner, for example, by screw 32 and hand wheel 33.

A tool holder block or support 34 of any conventional type is suitably supported on the carriage 31. This tool holder block 34 accommodates one or more tool holders 35 of conventional type. Individual set screws 36 serve to clamp individual ones of the tool holders with respect to the block 34 in well known manner. Chisels, knives or other cutting tools or elements 37 are suitably supported on the tool holders 35. These cutting elements 37 may be individually adjusted or removed from the respective tool holders, in conventional manner.

It will be seen that the provision of the two carriages 26 and 31 which are movable at right angles to each other by manipulation of the respective handwheels 29 and 33 permits two directional adjustments of the tool holder block 34 and consequently of the tool holder or holders 35 carried thereby so that both depth of cut and location of cut by cutting element or elements 37 can be effected.

In operation of the apparatus thus far described, one or more of the wire cored rims or straps previously removed from tires, or other cored straps which are in the form of endless bands B (Fig. 2) are placed upon the two pulleys 14 and 23. The hand wheel 17 is then manipulated to move carriage 11 and with it pulley 14 away from pulley 23 to tension the bands on the pulleys 14 and 23. The motor 22 is then started and the bands are driven around the pulleys 14 and 23. The teeth 24 enhance the driving effect of pulley 23 by biting into the body of material surrounding the wire cores in bands B increasing the positive or frictional drive.

As clearly disclosed by Figs. 1 and 2, the pulleys 14 and 23 have concave work-carrying surfaces. The machine is designed to handle a plurality of bands B, as indicated by broken lines in Fig. 2, and the concavities of the pulleys produces the new and unexpected result of causing the bands to ride together to form a group with each band bracing itself against another. The problem of handling tire beads, removed from old tire carcasses, has caused those skilled in the art to use elaborate machines for removing the tire wire from the beads prior to severing the latter from the tire carcasses. As just described, the present invention solves this problem.

The hand wheels 29 and 33 are then manipulated so as to properly position the cutting edges of the cutting tool or tools 37 with respect to the moving surfaces of the pulley-mounted, wire-cored rims or straps so as to cut into the soft bodies thereof. The position of the cuts on the straps or bands is regulated by manipulation of hand wheel 33, while the depth of cut or incision is regulated by manipulation of hand wheel 29. The number of cutting tools 37 utilized at once depends upon the dimensions of the wire cored rims or straps and the number thereof mounted as bands on the pulleys 14 and 23 at any time. After the cutting tool or tools 37 have been adjusted for position by hand wheel 33 the depth of cut is adjusted by hand wheel 29 and is also in-

creased thereby until the cutting edge or edges of tool or tools 37 reach the wire cores in the body or bodies of the bands B. The incision or cuts in the body, of course, are continued until they extend substantially over the entire periphery of the endless rim or bands to the depth of the wire core. Then the cutting tools 37 are withdrawn, the motor 22 stopped, the pulley 14 moved toward pulley 23 and the so cut or incised rims or straps removed from the pulleys 14 and 23.

Since the body of material surrounding the wire cores usually includes rubber or other resilient material the cuts or incisions tend to close and must be spread apart to expose the wire cores so that a hooked instrument 39 may be inserted to engage the wire core, so that the latter may be stripped from its surrounding body.

To this end a suitable clamp or vise may be utilized. For example the vise or clamp shown in Fig. 3 may be utilized. This vise comprises a fixed jaw 40, a movable jaw 41 and teeth 42 and 43 on the faces of the jaws 40 and 41. The fixed jaw 40 is supported on a suitable fixed base 44. The movable jaw is slidably carried on a suitable support 45 by its guide portion 46, the latter extending through a suitable guideway 47 provided in the body of the fixed jaw 40. Any other conventional means for guidedly supporting the movable jaw 41 relative to the fixed jaw 40 may be employed.

The movable jaw 41 is moved toward and away from the fixed jaw 40 in any conventional manner, for example, by use of the screw 48 and manipulating handle 49, in well known manner.

In use the rims or straps that have been previously cut or incised as hereinbefore described are placed between the jaws 40 and 41. Jaw 41 is then moved toward jaw 40 to clamp a portion of the body of the previously incised rim or strap between the jaws. The clamping action causes the teeth 42 and 43 to grip the soft body of the core and to spread the cuts in the upper surface of the rims or straps. The hook end 39' of the hooked instrument 39 is then inserted into the spread incisions or cuts and the wire core or ring stripped from the surrounding body.

It is to be understood that the apparatus is capable of use for extraction of cores other than wire from soft surrounding bodies.

While a specific embodiment of the invention has been described, it should be understood that structural changes are contemplated within the scope of the appended claims. There is no intention of limitation to the exact details shown and described.

What is claimed is:

1. Apparatus for the extraction of ring-like wire cores from their surrounding bodies comprising a support table, a movable carriage, a pulley rotatably supported on said carriage, means for moving said carriage reciprocally on said support table, a second pulley, means for supporting said second pulley, toothed means on said second pulley, means for rotating said second pulley, a second support table having a guideway, a reciprocally movable carriage slidably in said last-named guideway, means for reciprocally moving said last-named carriage, said last-named carriage being movable in a direction parallel with that of said first-named carriage, said second-named carriage having a guideway, a third carriage slidably supported in said last-named guideway and movable reciprocally therein in a direction transverse to the direction of motion of said first and second-named carriages, a tool support

carried by said third-named carriage, and cutting means mounted from said tool support, the said ring-like cores and surrounding bodies being mountable over said pulleys and moved thereby when tensioned by movement of said first-named pulley on its carriage away from said second-named pulley and when said second-named pulley is driven, and said cutting means being adjustable both as to position relative to said so mounted ring-like cores and bodies and as to depth of cut into said bodies by appropriate movement of said second and third-named carriages.

2. Apparatus for the extraction of wire cores from beads previously separated from tires, said beads remaining in the form of endless bands, comprising a support table having a guideway, a movable carriage slideable reciprocally in said guideway, means for reciprocating said carriage, a pulley supported for rotation from said carriage, a second pulley, means for supporting said second pulley from said table, means for driving one of said pulleys, frictional means in conjunction with at least one of said pulleys, said endless bands being mountable over said pulleys and moved thereby when tensioned by the movement of said first-named pulley on its carriage away from said second-named pulley and when said driving means is actuated, a second support table immovable relative to said first-named table, said second table having a guideway, a reciprocally movable carriage slideable in said last-named guideway, means for reciprocally moving said last-named carriage, said last-named carriage being movable in a direction parallel with that of said first-named carriage, said second-named carriage having a guideway, a third carriage slideably supported in said last-named guideway and movable reciprocally therein in a direction transverse to the direction of motion of said first and second-named carriages, a tool support carried by said

third-named carriage, cutting means mounted from said tool support, said cutting means being adjustable both as to position relative to the pulley-mounted beads and as to depth of cut into said beads by appropriate movement of said second and third-named carriages, means for clamping the cut beads subsequent to their removal from said pulleys to spread the incisions made by said cutting means to expose the cores and means for extracting the so-exposed cores.

3. A machine for removing tire wire from tire beads separated from tire carcasses, said machine being characterized by including at least two variably-spaced pulleys over which a plurality of said tire beads may be stretched and which have concave tire bead carrying surfaces causing said tire beads to clamp with each supported by another, said machine further including means for rotatively powering at least one of said pulleys and means for mounting at least one tire bead cutter for movement into cutting relation with tire beads when they are looped over said pulleys as described.
